TICK-TACK-TOE GAME APPARATUS

Richard R. Schram, South Gate, Calif., assignor of ten percent to Martin Nagy, Downey, and ten percent to Simeon P. Owens, South Gate, Calif.

Filed Sept. 29, 1961, Ser. No. 66,909

Term of patent 14 years

(Cl. D34—5)

Fig. 1.

Fig. 2.

Fig. 3.

FIG. 1 is a top plan view of a tick-tack-toe game apparatus showing my new design.

FIG. 2 is a side elevational view thereof.

FIG. 3 is an end view.

The side and end that are not shown are respectively the same as the side and end that are shown.

I claim:

The ornamental design for a tick-tack-toe game apparatus, substantially as shown and described.
